UNITED STATES PATENT OFFICE

HARRY SEBELL, OF BOSTON, MASSACHUSETTS, ASSIGNOR TO ARTHUR H. PARKER, OF LEXINGTON, MASSACHUSETTS

SEALED CAN

Application filed June 4, 1929. Serial No. 368,247.

This invention relates to cans such as are used for packaging paint, food and other materials and particularly to cans which are provided with a removable cover.

5 One object of the invention is to provide a novel construction by which the removal of the cover may be facilitated when the can is to be opened.

In the can embodying my invention the 10 can body has an outwardly-extending flange which mates another outwardly-extending flange formed on the can cover.

One of said flanges is a multi-ply flange with portions thereof having a reduced number of plies on the face thereof adjacent the 15 other flange whereby pockets are formed between the flanges into which an implement may be inserted to pry the flanges apart.

In order to give an understanding of the 20 invention I have illustrated in the drawings some selected embodiments thereof which will now be described after which the novel features will be pointed out in the appended claims.

25 Fig. 1 is a side view of a can embodying my invention;

Fig. 2 is an enlarged sectional view on the line 2—2, Fig. 1;

30 Fig. 3 is an enlarged sectional view on the line 3—3, Fig. 1;

Fig. 4 is a fragmentary plan view of a portion of the cover showing a step in the process of making it;

35 Fig. 5 is a similar view showing the cover completed;

Fig. 6 is a section on the line 6—6, Fig. 4, said figure showing in dotted lines how the thickened portion of the flange is formed;

40 Fig. 7 is a perspective view illustrating a can cover having a slightly different construction from that shown in Figs. 1 to 5 and in one formative stage;

Fig. 8 is a section on the line 8—8, Fig. 7;

45 Fig. 9 is a section on the line 9—9, Fig. 7, but showing one of the fingers or extensions of the cover rolled up;

Fig. 10 is a fragmentary sectional view 50 through a closed can having the cover construction shown in Figs. 7, 8 and 9;

Fig. 11 is a view illustrating the manner in which the cover may be pried loose;

Fig. 12 is a fragmentary sectional view through one side of the can body.

In the drawings 1 indicates a can body and 55 2 indicates a removable cover by which the can body is closed or sealed. The can body and can cover are each provided with outwardly-extending flanges which flanges mate each other when the cover is in closing relation. If the can is to be sealed the sealing 60 may be accomplished in any manner commonly employed for making a tight joint between the cover and the can body.

The flange on the can body is indicated at 65 3 and in the particular embodiment herein shown said flange projects outwardly from the can body and is located at a distance below the upper edge 4 of the body so that the can body has an upstanding portion 5 located 70 above the flange 3.

In the present embodiment of the invention the cover 2 is shown as having a depending skirt portion 6 which embraces the upper portion 5 of the can body and said can 75 cover has the outwardly-extending flange 7 located at the lower end of the skirt 6, which flange 7 mates the flange 3.

As stated above one of the features of the 80 present invention relates to a novel construction by which the mating flanges 3 and 7 are formed with pockets adapted to receive a screw driver or other similar implement for the purpose of prying the flanges apart when the can is to be opened.

These pockets are formed by making certain portions of one of the flanges thicker than other portions thereof so that when the flanges are in sealing relation pockets will be formed at the thinner portions of the 85 flange. These thicker and thinner portions may be formed on either flange without departing from the invention but I will preferably form them on the flange 7 of the cover.

The drawings show two ways in which this 90 may be done. In the construction shown in Figs. 1 to 6 inclusive the cover 2 is made initially with a two-ply outwardly-extending flange 7 at the lower edge of the skirt portion 6 as illustrated in Fig. 6, this two-ply 100

flange being formed by folding the material thereof back on itself. The two-ply flange thus formed is then slit radially at frequent intervals as shown at 9 in Fig. 4 and the portions 10 between certain adjacent slits 9 is folded back underneath the flange 7 as shown at dotted lines in Fig. 6 thus making a four-ply flange portion. The flange thus made will present two-ply portions 11 of the full width and other four-ply portions 12 of less width than the portions 11 but of extra thickness due to the folding over of the portions 10 of the flange. The completed cover thus has an outwardly-extending flange 15 which is provided with portions 11 which are thinner than the portions 12 and the extra thickness of the portions 12 is located on the under side of the flange. When the cover thus made is applied to the can the thicker portions 12 will rest on the flange 3 of the can body while the thinner portions 11 of the flange 7 will be spaced from the flange 3 of the can body thereby providing pockets 13.

When the can is to be opened a screw driver or other implement 14 may be inserted into one of the pockets 13 and then manipulated to pry the flanges apart. If the can is hermetically sealed, as is done in the case of cans which contain canned food there will exist a considerable vacuum in the can which it is necessary to break in order to remove the can cover. By providing the pockets 13 adapted to receive a screw driver or other implement the operation of loosening the cover and breaking the vacuum is greatly facilitated and can be easily accomplished by anyone.

In Figs. 7 to 12 I have shown a different embodiment of the invention. In this embodiment the flange of the can cover has a uniform width all the way around but is nevertheless provided with thicker and thinner portions. A can cover having this construction may be made from a blank such as shown in Fig. 7 which illustrates a sheet of material which has been struck up into the form of the cover with the depending skirt portion 6 and with the flange 15 extending laterally therefrom, said flange being formed initially with a plurality of fingers or extensions 16. These fingers or extensions are rolled or folded up underneath the flange 15 as shown at 17 in Fig. 9 and after this rolling or curling process the rolled portion 17 is preferably flattened as shown in Fig. 10. The cover thus made will have a flange 15 of uniform width but with thicker multi-ply portions 17 which are formed from the rolled up or folded fingers 16 and thinner portions having a reduced number of plies between the thickened portions 17. In the places or portions where they are fewer, the reduction in the number of plies is on the face of the flange which is directed toward the other

flange so that pockets will be formed between the flanges where the plies are omitted.

When a cover having this construction is placed on the can the thickened portions 17 of the cover will rest on the flange 3 of the can body and pockets 13 will exist between the flange 3 on the can body and the thin portion of the flange 15 on the can cover. In this construction the flange 15 is of uniform width. 75

In order to facilitate the removal of the cover after it has been loosened I will preferably provide said cover with a peripheral bead adjacent its top. This bead may be formed either by deforming or upsetting the metal of the cover as shown at 18 in Fig. 9 or may be formed by placing a wire 19 around the cover and soldering it thereto. In either case the cover is provided with an annular bead which forms a finger hold to enable a person to firmly grasp the cover and pull it off from the upstanding portion 5 of the can body. 80

While I have illustrated herein some selected embodiments of my invention I do not wish to be limited to the constructional features shown as there are other ways in which the invention might be embodied. 90

I claim.

1. A can comprising a can body having an outwardly-directed flange, a can cover having a mating flange, one of said flanges being a multi-ply flange and having at certain portions thereof fewer portions than at other portions, the reduction in the number of plies being on the face of said flange adjacent the other flange whereby pockets are formed between the flanges for the reception of an implement to be used to pry the flanges apart. 95

2. A can presenting a can body having an outwardly-directed flange, a can cover having a multi-ply flange mating that of the can body, the flange of the can cover having portions which have a reduced number of plies with the remaining plies at such portions spaced from the flange on the can body, whereby pockets are formed between the flanges into which an implement may be inserted to pry said flanges apart when the can is to be opened. 100 110

In testimony whereof, I have signed my name to this specification.

HARRY SEBELL.
